United States Patent

Des. 241,892

Patented Oct. 19, 1976

241,892

STAND FOR POTTED PLANTS OR THE LIKE

Doris Sweeney, 512-A Taylor Ave., Warrington, Pa.
18976, and Mary Ellen Lee, 7915 Anita Drive, Philadelphia, Pa. 19111

Filed Apr. 30, 1975, Ser. No. 573,022

Term of patent 14 years

Int. Cl. D6—04

U.S. Cl. D6—27

FIG. 1

FIG. 2

FIG. 3

FIG. 4

FIG. 1 is a front elevational view of a stand for potted plants or the like showing our new design.

FIG. 2 is a top plan view thereof.

FIG. 3 is a bottom plan view thereof.

FIG. 4 is a rear elevational view thereof.

We claim:

The ornamental design for a stand for potted plants or the like, substantially as shown.
